APPARATUS FOR USE IN THE MANUFACTURE
OF SHOES

Agenor Eugene St. Germain, Haverhill, Mass.

Application January 13, 1951, Serial No. 205,868

6 Claims. (Cl. 12—1)

This invention relates to apparatus for use in the manufacture of shoes, and especially to the manufacture of force lasted shoes of the California type.

In the manufacture of the California type shoe, which is characterized by a platform sole and/or wedge heel, covered with a wrapper strip, the upper, including the forepart and quarters, a sock lining which may constitute the insole, and a wrapper strip are stitched along a common margin with the wrapper folded upwardly against the surface of the upper. A tuck is placed on the sock lining at the heel end thereof and cemented thereto to add stiffness to the shoe bottom at its heel end and when a wedge heel is used the tuck piece breaks the joint between the wood portion of the heel and the forward portion of the wedge, thus insuring a smooth surface for the foot to rest upon. After the tuck piece is applied, it is allowed to set until dry, whereupon the wrapper is turned so as to stand substantially vertical to the surface of the sock lining in readiness for placing the platform and/or heel on the sock lining and lasting the wrapper over the bottom thereof. The external surface of the heel wedge slopes inwardly toward its bottom and so in order to secure a snug fit, the wrapper is cut with less material along its free edge than at its attached edge. The shortened upper portion of the wrapper snugly embraces the rear part of the upper, particularly over the counter bulge, the upper margin actually extending beyond the bulge and being shorter in length than the girth of the bulge, hence it is extremely difficult to pull the snugly fitting wrapper strip downwardly over the bulge. In addition to the snugness of the wrapper, the folding of the material upon itself takes up any slack that might be afforded by the elasticity of the material itself and so aggravates the condition, making it nearly impossible to turn the wrapper without overstressing it and breaking the stitching joining it to the lower edge of the upper. Difficulty is also experienced at the tip of the shoe, although not nearly so great. Because of the foregoing difficulties in turning, operators were prone to break the assembly at about the location of the breast of the heel to provide slack in the wrapper to make it easier to turn. This breaking of the assembly was usually so severe as to break the tuck piece transversely and make it ineffective for its intended purpose of stiffening the shoe.

The principal objects of this invention are to provide an apparatus for use in operating on an upper assembly of the foregoing kind to permit turning the wrapper easily without destroying the effectiveness of the tuck piece and without damaging the wrapper material or pulling it away from its junction with the upper. Further objects are to provide an apparatus which is of simple, durable construction and which will very much simplify assembling the tuck piece with the upper assembly and turning the wrapper without need for lasting pinchers or other mechanical lasting apparatus.

In the operation of the apparatus, an assembly of the upper including the forepart and quarters joined in circular fashion, a sock lining and a wrapper strip united along common margins by stitching with the upper folded upwardly against the wrapper, is gripped firmly throughout a substantial portion of the heel end of the sock lining close to the stitched margin thereof, and then the forepart of the upper is bent transversely along a smooth curve, beginning at the breast line of the heel end of the shank and extending forwardly thereof to at least the ball line so as to shorten the overall length of the

2

assembly. Shortening the overall length of the assembly relieves the stress in the wrapper, providing an excess thereof, so that the wrapper may then be gripped and pulled outwardly and downwardly or upwardly over the counter bulge as the case may be, so as to stand up substantially vertical to the plane of the sock lining. Preferably adhesive is applied to the heel end portion of the sock lining and a tuck piece which extends forwardly at least throughout the shank is laid on the sock lining prior to gripping, bending and turning of the wrapper, so that during the time required to bend the assembly and turn the wrapper, the adhesive will have had time to set and thus unite the tuck thereto.

The apparatus as herein illustrated, has spaced, relatively movable members arranged initially to be brought into engagement with the opposite surfaces of the sock lining to hold it firmly, and then to bend the forepart of the upper transversely and throughout the shank portion to foreshorten the assembly. One of the members which constitutes a hold-down, has a narrow, longitudinally convex surface of approximately the contour of the sock lining and the other, which constitutes a jack, has an initially flat surface of substantially the same shape which, when brought into engagement with and pressed against the one member, may be made to conform to the convex surface thereof, thereby bending the assembly into contact with the convex surface of the one member. The jack consists of a plurality of articulated parts mounted for movement to and from the hold-down, which is fixed, and there is linkage for initially moving the jack toward the hold-down to bring their heel end portions together and thereafter to roll the remainder of the jack into contact with the convex portion of the hold-down.

35 The invention will now be described in greater detail with reference to the accompanying drawings, wherein:

Fig. 1 is a side elevation of the machine showing the operating parts spaced in their at-rest positions;

Fig. 2 is an end elevation of the device as seen from 40 the left-hand side of Fig. 1;

Fig. 3 is a vertical section taken on the line 3—3 of Fig. 2;

Fig. 4 is a vertical section taken on the line 4—4 of Fig. 1;

45 Fig. 5 is a fragmentary elevation showing an upper assembly mounted on the device in readiness to be operated upon;

Fig. 6 is a corresponding elevation showing the initial step in operating upon the upper;

50 Fig. 7 is an elevation partly in section showing the ultimate position of the parts in operating on the assembly prior to turning the wrapper;

Fig. 8 shows the upper held between the operating parts with the wrapper partially turned at the heel end; 55 and

Fig. 9 is a plan view of the apparatus taken on the line 9—9 of Fig. 6.

Referring to the drawings (Fig. 1), the device has a base 10 of suitable rigidity and height to support the 60 operating parts in a convenient position for an operator standing in front of the machine, to the top of which is bolted an upright gooseneck comprised of a vertical portion 12, a horizontal overhanging portion 14 and a downwardly and inwardly inclined bill 16. A narrow, rigid, bent plate 18 having a substantially horizontal rear part 20 and an inclined forward part 22 is fastened by screws 24 to the forward and lower surfaces of the bill and constitutes a fixed hold-down for holding the shoe as will appear hereinafter, during the turning operation. The bent plate corresponds substantially in plan to the shape of a sock lining or insole. A facing member 26 of somewhat resilient material, for example, cork or hard rubber, is preferably attached to the surface of the plate 18 so as to avoid damage to the shoe parts.

70 The vertical portion 12 of the gooseneck has a base flange 28 which extends forwardly from the base 10 and has integral therewith a vertically arranged flange plate 30. A substantially rectangular, elongate frame 32 is bolted in an upright position to the face of the flange 30 by means of bolts 34 and has in it a vertical

narrow slot or opening 36. Vertically aligned holes 38 are formed in the upper and lower ends of the frame 32 and through these holes there is placed a rod 40. A C-shaped frame 42 having spaced parallel arms 44 pierced to receive the rod 40 is slidably mounted within the slot 36 on the rod 40 and has attached to its forward face a bar 46, by means of screws 48. As thus arranged, the bar 46 is substantially parallel to the rod 40, and may be moved relatively thereto. A compression spring 50 is mounted on the rod 40 between the lower arm 44 of the frame 42 and a collar 52 fixed to the rod. In its uncompressed condition, the spring holds the frame 42 against the lower end of the frame 32 so that the upper ends of the bar 46 and the rod 40 are at approximately the same level.

A jack is mounted on the upper end of the rod 40 and bar 46 for movement to and from the fixed hold-down. As illustrated, the jack has a normally flat supporting surface on which the upper assembly may be placed but is deformable and consists of three sections 56, 58 and 62 hinged together. The section 56 is pivotally connected to a subjacent block 54 fast to the upper end of the rod 40. The section 62 is pivotally connected to the upper end of the bar 46. The section 58 is pivotally connected at its opposite ends to the sections 56 and 62. As constructed, the block 58 has at opposite ends spaced ears which embrace the forward and rear ends of the blocks 56 and 62, through which hinged pins 60 and 64 pass so that the sections or blocks 56, 58 and 62 are free to be moved angularly relative to each other, that is the blocks 56, 58 and 60 provide an articulated body which normally has a flat upper surface conforming in contour substantially to a projection of the hold-down plate 26 on a flat surface, but which may be bent to take the convex shape of the hold-down plate 26 when moved into engagement therewith.

To effect upward movement of the jack and conformation thereof to the curved surface of the hold-down, a link 66 having bifurcated ends is pivotally attached by a pin 68 to the upper arm 44 of the bracket 42 and to the forward end of a lever 70 fulcrumed at 74 in a slot 72 at the base of the gooseneck. The rear end of the lever 70 is connected to the upper end of a treadle rod 76, the lower end of which terminates at the base of the machine and has fast thereto a suitable treadle for depressing it and a return spring for elevating it.

In operation of the device, an upper assembly *u* consisting of a forepart *f* and quarters *q* stitched in circular fashion, a sock lining *s* and a wrapper strip *w* joined along common margins by stitching *t* as shown in Fig. 5 is placed bottom up on the jack with the heel end thereof engaged with the rear end of the jack. As illustrated, the wrapper is folded upwardly against the upper material and it is noted that the free edge thereof, being somewhat shorter than the stitched edge, hugs both the curvature of the counter at the heel end and the tip portion of the toe. It is to be understood that the assembled upper may and usually will have a counter and counter lining stitched in place at the heel. Adhesive is then applied to the rear end of the sock lining and a heel tuck piece is laid down on the cement coated surface and properly positioned by the operator. The treadle is then operated to draw the treadle rod 76 down and hence to elevate the C-frame 42, which in turn raises both the rod 40 and the bar 46 so as to elevate the jack to the level shown in Fig. 6, in which position the rear block 56 presses the rear end portion of the sock lining resting on it, in to engagement with the lower rear portion of the hold-down 26. At this stage in the operation, and before any considerable amount of pressure is applied, the operator may shift the upper forwardly and laterally so that it is in proper registry with the operating parts and may also adjust the position of the tuck piece so that it fits exactly in place. Upon further depression of the treadle, the C-frame 42 continues to rise relative to the rod 40 which is stopped by engagement of the block 56 with the rear end of the hold-down, against the spring 50. As the bar 46 rises, the block 58 pivots about the pin 60 and the block 62 pivots about the pin 64 so that these parts conform and are brought into surface contact with the upwardly inclined surface of the hold-down 26, thereby flexing or bending the sock lining and upper assembly as illustrated in Fig. 7, and shortening its overall length.

With the upper and tuck piece bent as illustrated, if the latter is used, and firmly clamped between the hold-down

and jack, there will be considerable slack in the wrapper and this is now grasped and turned by pulling it outwardly and upwardly as shown in Fig. 8 until it is substantially perpendicular to the plane of the sock lining. This can be done without straining the wrapper due to the foreshortening of the upper, which when bent, relaxes the wrapper and provides an excess of material, so that it can be easily turned to insure a good even line, where the wrapper turns outwardly from the lower margin of the upper without using lasting pinchers. The treadle is then released and the parts separated, whereupon the upper with the wrapper folded perpendicular to the sock lining may then be removed for receiving the bottom member which consists of a platform sole and/or wedge heel as the case may be. The tuck piece will be firmly united to the sock lining during the gripping and turning operations. It is to be understood that the tuck piece may be omitted if the type of shoe warrants it.

It is to be noted that the contour of the hold-down is of such shape that while it bends the sock lining, tuck piece and upper, the bending takes place throughout the shank and is gently curved to conform to the hold-down without permanent damage to the tuck piece or the stitching at the shank portion of the upper.

While the jack is illustrated as consisting of articulated sections, it is within the scope of the invention to employ any suitable deformable member which when moved into engagement with the convex surface of the hold-down will conform thereto, for example, a strip of spring steel, a block link chain, or an inflatable member.

It should be understood that the present disclosure is for the purpose of illustration only and that this invention includes all modifications and equivalents which fall within the scope of the appended claims.

I claim:

1. Apparatus for operating upon an upper assembly consisting of an upper, a sock lining and a wrapper united along a common margin by stitching with the wrapper folded upwardly against the side of the upper, comprising spaced, relatively movable members arranged to be brought into engagement with the heel end portion of the sock lining, one of said members having a rigid, narrow surface corresponding substantially in length and contour to the shank and heel end of the sock lining, said surface being longitudinally convex, and the other being longitudinally articulate so that when pressed against the convex surface of the rigid member, it will conform thereto, and means for effecting relative movement of the members to bend an upper assembly therebetween to shorten its overall length.

2. Apparatus for operating upon an upper assembly consisting of an upper, a sock lining and a wrapper united along a common margin by stitching with the wrapper folded upwardly against the side of the upper, comprising spaced, relatively movable members arranged to be brought into engagement with the heel end portion of the sock lining of the upper assembly, one of said members having a rigid narrow surface corresponding substantially in length and area to the shank and heel end of the sock lining, said surface being longitudinally convex, and the other having longitudinally articulate portions, and means for effecting relative movement of the members to bring a portion of the articulate member into engagement with a portion of the rigid member near the heel end thereof, and then progressively to wrap the remainder of the articulate portions into engagement with the curved surface of the rigid member.

3. Apparatus for operating upon an upper assembly consisting of an upper, a sock lining and a wrapper united along a common margin by stitching with the wrapper folded upwardly against the side of the upper, comprising spaced, relatively movable members arranged to be brought into engagement with the heel end portion of the assembly, one of said members having a rigid narrow surface corresponding substantially in length and shape to the shank and heel end of the sock lining, the heel end portion of which is substantially parallel to the other member and the remainder of which diverges therefrom, said other member having an initially flat surface corresponding substantially in outline to a projection of the one member on a flat surface, and being longitudinally deformable, means for effecting relative movement of the members to bring the heel end portions of the members into contact and thereafter progressively to roll the re-

mainder of the deformable member into engagement with the diverging portion of the rigid member.

4. Apparatus for operating upon an upper assembly consisting of an upper, a sock lining and a wrapper united along a common margin by stitching with the wrapper folded upwardly against the side of the upper, comprising spaced, relatively movable members arranged to be brought into engagement with the heel end portion of the sock lining of an upper assembly, one of said members having a rigid narrow surface corresponding substantially in length and outline to the shank and heel end of a sock lining, the heel end of which is substantially parallel to the other member, and the forepart of which diverges therefrom, said other member having an initially flat surface corresponding substantially in outline to a projection of the one member on a flat surface and being longitudinally articulate, and means operable to effect an initial engagement of the members at their heel ends and thereafter progressively to roll the remainder of the articulate member into contact with the diverging portion of the rigid member.

5. Apparatus for operating upon an upper assembly consisting of an upper, a sock lining and a wrapper united along a common margin by stitching with the wrapper folded upwardly against the side of the upper, comprising spaced, relatively movable members arranged to be brought into engagement with the heel end portion of the sock lining of the upper assembly, one of said members having a rigid narrow surface corresponding substantially in length and outline to the shank and heel end of the sock lining, the heel end of which is substantially parallel with the other member, and the forepart of which diverges therefrom, said other member having a plurality of articulate parts normally lying in a common plane, linkage connected to the articulate member to effect an initial movement thereof into engagement with the rigid member to bring the heel end portions together without deformation of the articulate member, and a further movement of the articulate member to cause the articulate parts forwardly of the heel end to be pressed into engagement with the diverging portion of the rigid member.

6. Apparatus for use in shoe manufacture comprising

a fixed part having a rigid narrow surface corresponding substantially in length and contour to the shank and heel end of a sock lining, the heel end of which is substantially horizontal and the forward part of which is inclined forwardly and upwardly therefrom, a movable part consisting of a plurality of articulate sections normally occupying a common plane situated below the fixed part and parallel to the horizontal portion thereof, said sections having an overall shape corresponding substantially to the projection of the fixed part on a flat surface, a bracket below the movable part having vertically spaced registering holes therein, a rod mounted for vertical movement in said holes, the upper end of said rod being pivotally connected to the heel end section of the movable part, a bar arranged parallel to the rod and slidably mounted thereon for movement relative thereto, the upper end of said bar being pivotally connected to a forward section of the movable part, a spring on the rod yieldably holding the upper end of the bar at the same level as the upper end of the rod so that the articulate sections are in a common plane, linkage connected to the bar for lifting it and hence the rod toward the fixed part to engage the heel end section of the movable part with the heel end portion of the fixed part and thereafter to raise the bar relative to the rod to engage the forward section of the movable part with the upwardly inclined, forward portion of the fixed part.
